UNITED STATES PATENT OFFICE.

PAUL KARCSAK, OF NEW YORK, N. Y.

BUTTON-SECURING DEVICE.

Application filed November 2, 1927. Serial No. 230,407.

This invention relates to devices for securing buttons to fabrics and has particular reference to attaching buttons of considerable size to articles of clothing.

5 It is a well known fact that buttons occasionally become loose or are actually loose, due to the breaking of threads with which they are fastened and a needle with suitable thread may not be conveniently at hand to 10 make the necessary repairs.

It is therefore one of the objects of the present invention to provide an efficient and simple means for attaching buttons wherever they may be desired, either originally or 15 when repairs are required, in a rapid and effective manner.

A further feature is to provide such means in forms convenient for use and which may be applied without the necessity of a needle 20 and thread or other like tools and accessories.

These and other analogous objects, such as 25 neatness of appearance, security and ease of application, are accomplished by the novel construction and combination of parts, hereinafter described and shown in the annexed drawing, forming part hereof, and in which:—

Figure 1 is a plan view of a button as fastened by an embodiment of the invention.

30 Figure 2 is a transverse sectional view taken on line 2—2 of Figure 1.

Figure 3 is an expanded view of the several parts, showing the sequence of their arrangement.

35 Figure 4 is a view similar to Figure 1 but illustrating the application of the device to a button having four openings.

Figure 5 is a perspective view of the 40 pronged elements used in connection with the showing in Figure 4.

As shown in the drawings, a piece of any textile fabric, generally designated by the numeral 10, indicates the material to which a button 11 is to be secured.

45 The button, illustrated in Figures 1 and 2, is of conventional type, having a pair of spaced openings 12, or as in Figures 3 and 4, with four similar openings 12^a.

If only two openings are used, a single 50 round metallic wire fastener is used, the fastener presenting a bar portion 13 integrally

connecting right angled members 14 terminating in sharp ended, outturned hook-like prongs 15, capable of being passed through the button openings 12 or 12^a and also the fabric 55 10.

After these elements have been passed through the button eyes, a flexible ring 16, as of rubber or a closely wound spring, is slipped over the elements 14, as best seen in Figure 2, 60 and then the prongs are passed through the material 10.

Thereafter, a similar ring 17 is engaged over the extending ends of the elements 14, 65 then projecting through the side of the material opposite the button, and the prongs 15 will retain the ring 17 and button securely to the fabric.

In Figures 4 and 5, in place of a single retainer, two are used, arranged at right angles 70 and affording a double grip, the rings 16 and 17 confining the retainers in the manner before noted.

It will be seen that the function of the ring 16 is that of a spacer, holding the button 75 slightly away from the material, and the ring 17 acts to confine the prongs, preventing the button to be pulled off or away from the fabric.

Although my invention has been described 80 with reference to a particular embodiment, it is understood that minor changes in construction and details thereof may be made without departing from the scope of the claim hereto appended.

Having thus described my invention, what I claim as new and desire to secure by Letters Patent, is:—

A button fastener comprising one or more 90 two pronged wire loops having out-turned hook ends adapted to pass through the eyes of a button and material to which it is attached, a flexible spacing ring circumjacent the prongs of the hooks intermediate the back of the button and material, said ring being composed of a closely wound helical spring wire and a second similar flexible ring to engage the protruding ends of the loop to seat in the hooked elements thereof.

In witness whereof I have affixed my signature.

PAUL KARCSAK.
